UNITED STATES PATENT OFFICE.

GEORGE A. HOFFMAN, OF PHILADELPHIA, PENNSYLVANIA, ASSIGNOR
TO HUGO BILGRAM, OF PHILADELPHIA, PENNSYLVANIA.

TAPPING-MACHINE.

SPECIFICATION forming part of Letters Patent No. 774,357, dated November 8, 1904.

Application filed April 9, 1904. Serial No. 202,337. (No model.)

To all whom it may concern:

Be it known that I, GEORGE A. HOFFMAN, a citizen of the United States, and a resident of the city and county of Philadelphia, State of Pennsylvania, have invented certain new and useful Improvements in Tapping-Machines, of which the following is a specification.

My invention relates to improvements in machines for tapping nuts or similar articles; and the object of my invention is to furnish an automatic tapping-machine in which the tap will be continuously rotated in one direction.

In the accompanying drawings, forming part of this specification, and in which similar characters of reference indicate similar parts throughout the several views, Figure 1 is a plan of my tapping-machine or a view of Fig. 2 looking in the direction of the arrow in this figure; Fig. 2, a side elevation of my tapping-machine; Fig. 3, a section, enlarged, of Fig. 2 on line 3 3; Fig. 4, a section, enlarged, of Fig. 2 on line 4 4; Fig. 5, a central sectional elevation through the blank-conveyer, taken on line 5 5, Fig. 6; Fig. 6, a section of Fig. 5 on line 6 6; Figs. 7 and 8, perspective views of a nut before and after threading; Fig. 9, a section corresponding to the section shown in Fig. 3 of a modification of my machine; Fig. 10, a section of Fig. 9 on line 10 10; Fig. 11, a perspective view of tap-holder, Fig. 9; Fig. 12, a section of Fig. 9 on line 11 11.

a is the frame of my machine; *b*, a driving-pulley which drives a shaft *c*, which carries a bevel-gear *d*, which drives a bevel-gear *e*, which is carried on a shaft *f*.

Fast upon shaft *f* are the gears *g* *h*, which gear, respectively, with the gears *i* *j*, which are carried the first by a shaft *k*, the second by a shaft *l*.

m is a worm carried by shaft *f*; *n*, a worm-wheel gearing with worm *m*.

o represents collars carried by shaft *k*; *p*, collars carried by shaft *l*.

r is a lever pivoted at *s*, the upper end of which is bifurcated and engages collars *o*; *t*, a lever pivoted at *u*, the upper end of which is bifurcated and engages collars *p*.

1 is a pin carried by lever *r*; *2*, a pin carried by lever *t*.

3 4 are arms one end of each of which is 50 pivoted to the worm-wheel *n* at 5, the other ends being slotted, as shown at 6 7, Fig. 2. The pins 1 2, carried by levers *r* *t*, pass, respectively, through slots 6 7.

8 is a spring connecting levers *r* *t*.

9 is a tap the ends of which are squared and adapted to be engaged by sockets 10 11 in the ends, respectively, of shafts *k* *l*.

12 is a guide, in the present case stationary, which holds the nut-blanks 13 from turning 60 while being operated upon by the tap.

14 is a magazine from which the nuts are fed to the guide 12.

The operation of the machine is as follows: The blanks 13 are fed to the magazine 14 in 65 any suitable manner and fall from this guide to the guide 12, being prevented from entering this latter guide until the proper time by the end of the shaft *k*, which enters one end of the guide 12, as shown in Fig. 3. The pulley *b*, being driven, drives, through shaft *c*, the bevel-gear *d*, which drives bevel-gear *e*, which drives shaft *f*. The shaft *f* drives the gears *g* *h*, which drive the gears *i* *j*, which drive the shafts *k* *l*, the sockets 10 11 in these shafts 75 driving the tap 9. With the rotation of shaft *f* is rotated the worm *m*, which drives the worm-wheel *n*, the rotation of which causes, through arms 3 4, the alternate rocking of the arms *r* *t*, which disconnect alternately the 80 shafts *k* *l* from the tap 9, the shafts *k* *l* being free to slide in their bearings in frame *a* and the gears *i* *j* being secured to their respective shafts by splines 15, so that the shafts may 85 also slide through these gears. When the arm *r* is rocked out, its bifurcated upper end engages the outer collar *o* on shaft *k* and moves this shaft out until its inner end is completely clear of the end of the tap 9 and until a sufficient space is left between the end of the tap 90 and the end of the shaft *k* for the entrance of a blank from the magazine 14. In the meantime the tap is rotated by the shaft *l*, the socket 11 of which remains engaged by the squared end of the tap. A blank having entered the guide 12 from the magazine 14 and the wheel *n* having been moved so as to allow the arm 3 to be withdrawn, the spring 8 re-

turns the arm *r* to its first position, thereby moving in the shaft *k*, which pushes the blank just entered in guide 12 upon the tap 9, causing the shaft *k* to operatively engage the tap.

- 5 After the inner collar *o* abuts against the frame *a*, Fig. 3, the arm *r* will remain at rest, the slot 6 permitting the arm 3 to follow the movement of the pin 5 of the worm-wheel *n*. A further movement of the wheel *n* causes 10 the arm 4 to push out the lever *t*, which moves the shaft *l* out of engagement with the tap 9, permitting a blank that may have been threaded to fall down between the end of the tap and the end of this shaft. A further movement 15 of the wheel *n* causes the arm 4 to release the lever *t*, and the spring 8 returns this latter lever and the shaft *l* to their first positions.

In practice the shaft *f* and connected parts are inclined, as shown in Fig. 2, so as to facilitate 20 the discharge of the tapped blanks from the tap. The tap is prevented from falling from place when the shaft *l* is moved out of contact with it by the turning tap engaging the blanks within the guide 12. These 25 several parts coacting as a result of the friction of the nuts 13 against the guide 12 crowd the tap against the upper shaft *k*.

It will be observed that the tap is constantly rotated in one direction by either one 30 or the other, or by both, of the shafts *k* *l* and that the blanks 13 are constantly fed to and discharged from the tap.

In Figs. 9 to 12 a modification of my device is shown, in which the tap is held from rotation alternately by rods *k'* *l'*, which longitudinally are movable, but which do not rotate, the guide 12 surrounding the tap being the rotatable member instead of the fixed member as before shown and described.

- 40 In the modification the guide 12 is carried in a sleeve 16 and carries a gear-wheel 17,

driven by a gear-wheel 18 on the shaft *f*. In other respects the modification is substantially similar in construction to that already described. This modification is what is known 45 in kinematics as an "inversion," the tap being "rotated relatively to the guide" by the rotation of the guide.

Having thus described my invention, I claim as new and desire to secure by Letters Patent— 50

1. In combination, a tap having ends adapted to be engaged by sockets, socketed shafts adapted to alternately engage the opposite ends of said tap, means for carrying said shafts, means for alternately moving said shafts into and out of engagement with said tap, a blank-guide surrounding said tap, and means for rotating said tap relatively to said guide. 55

2. In combination, a tap having ends adapted to be engaged by sockets, socketed shafts adapted to alternately engage the opposite ends of said tap, means for carrying said shafts, means for alternately moving said shafts into and out of engagement with said 60 tap, a blank-guide surrounding said tap, means for rotating said tap relatively to said guide, and means for feeding blanks to said guide. 65

3. In combination, a tap having ends adapted to be engaged by sockets, socketed shafts adapted to alternately engage the opposite ends of said tap, said shafts and tap being inclined, means for carrying said shafts, means for alternately moving said shafts into and out of engagement with said tap, a blank- 70 guide surrounding said tap, and means for rotating said tap relatively to said guide. 75

GEORGE A. HOFFMAN.
